ROLLER SKATE

Daniel S. Williams, Pottstown, Pa.

Application July 11, 1958, Serial No. 51,746

Term of patent 14 years

(Cl. D34—14)

The figure is a perspective view illustrating the roller skate design.

The opposite side of the skate is of substantially the same configuration as the side shown in the drawing and the rear portion is of conventional configuration.

I claim:

The ornamental design for a roller skate, as shown and described.
